UNITED STATES PATENT OFFICE.

HERMANN SCHELLER, OF BERLIN, GERMANY.

ASH-CART.

SPECIFICATION forming part of Letters Patent No. 552,589, dated January 7, 1896.

Application filed May 31, 1895. Serial No. 551,299. (No model.)

To all whom it may concern:

Be it known that I, HERMANN SCHELLER, merchant, a subject of the King of Prussia, German Emperor, and a resident of Berlin, 5 in the Kingdom of Prussia, German Empire, have invented certain new and useful Improvements in Ash-Carts, of which the following is a specification.

This invention relates to dust or scavenging carts and is intended to so construct them that the dust fetched from dwellings may be put on the cart without causing any inconvenience by the spreading of the dust, that, further, the attendants may stand on the carts 15 without having close contact with the chambers receiving the dust, and, lastly, that the public may not be annoyed by the dust flying about or by the sight of the contents of the cart.

20 This improved cart is represented in the annexed drawings, in which—

Figure 1 is a longitudinal view; Fig. 2, a rear view, Figs. 3 and 4 being a longitudinal and a cross-section, respectively.

25 The interior of the cart, which is closed all round, is divided by cross walls A A' A² into several compartments, said walls being provided with door-like openings B, Fig. 4, also with a cross brace or bar c, so as to form a 30 joint or groove, into which the door or board C is inserted and kept in place by a bolt E. Above each of these compartments there is an opening G G G arranged in the top cover of said cart; the length of which opening cor-

35 responds with the length of the compartments A. Each opening is covered with a wire-netting of about one-inch mesh, and in addition may be closed by folding boards F F' F².

For filling the cart in the first place the wall 40 C is placed against that partition-wall A which is farthest from the door M. Then a removable curtain suspended on two bars is brought in front of the opening A, so that its lower end weighted with a round iron bar sewed 45 into it assumes a position inside the first compartment, as represented for partition A' of the second compartment. The top cover F of the foremost compartment being closed, the attendants enter the cart through the door M 50 and there empty the bucket, box or the like, by

tipping it up against the curtain H. These contents drop into the foremost compartment, while a spreading of the dust toward the outside is prevented by the curtain H. When this compartment is filled up to the upper 55 edge of the cross-wall C, the latter as well as the curtain H is brought to the middle partition-wall, and after the middle partition has also been filled up in like manner the same operation is repeated with the last compartment, in which latter instance the attendant stands in the small square space behind the doors M. In order to preclude the least escape of dust there is another curtain N attached to the entrance-door. 60

65 P is a side door by means of which the unloading of the dust on the dumping-ground is effected.

As a rule, the openings in the top cover are closed only before the loading of the respective compartments is to start, so that in the empty compartments good ventilation is obtained. This ventilation is essential, as the foul air concentrated in the cart would be detrimental to the health of the attendants. 70

75 What I claim is—

1. A dust or scavenging cart having inner cross walls A provided with doorlike openings, a plate C being inserted into the lower part of said openings, the upper part on the 80 inside of said walls receiving a curtain H, which latter is displaceable and suspended from the cover of said cart, substantially as set forth.

2. A dust or scavenging cart having in combination with the arrangements described for receiving dust and the like a ventilation arrangement G in the cover of said cart, consisting of openings F equal in their length to the width of the respective compartments 85 covered by a wire netting and clothed with folding boards or covers, substantially as set forth.

In testimony that I claim the foregoing as my invention I have signed my name in presence of two subscribing witnesses. 95

HERMANN SCHELLER.
